SCREEN CONTROL

Sydney Appel, Newark, N. J., assignor of one-third to William J. Foster, Little Ferry, N. J., and one-third to Samuel Appel, Newark, N. J.

Application August 25, 1938, Serial No. 226,757

4 Claims. (Cl. 156—35)

This invention relates to an improved screen control and has for an object to provide a construction wherein pull cables are provided for positively raising and positively lowering a screen.

Another object of the invention is to provide a control for a curtain, screen, or the like wherein the same may be moved upwardly and downwardly readily and held in any desired adjusted position by merely releasing the actuating means.

A further object, more specifically, is to provide in a screen control a pawl-and-ratchet structure associated with braking means, the parts being so arranged that the ratchet structure will rotate with the screen roller when the screen is being elevated but will remain stationary when the screen is being lowered.

In the accompanying drawing—

Fig. 1 is a vertical sectional view through a curtain and certain associated parts including a control embodying the invention, certain parts being shown in elevation;

Fig. 2 is an enlarged fragmentary sectional view through Fig. 1 approximately on the line 2—2;

Fig. 3 is a view similar to Fig. 2 but showing a modified construction;

Fig. 4 is a view similar to Fig. 3 but showing a further modified construction.

Referring to the accompanying drawing by numerals, 1 indicates a screen or curtain of any desired kind which is secured at one end to a pole or roller 2, which pole or roller is rotatably supported in brackets 3 and 4. In theatres and elsewhere it is desired to raise and lower the screen from time to time and to hold the screen in any desired adjusted position.

As indicated in Fig. 1, there are provided pulleys 5 and 6 which are pinned or otherwise rigidly secured to the pole 2 so as always to rotate therewith. Cables 7 and 8 are arranged to be wound on these pulleys, said cables being wound in opposite directions on the respective pulleys so that when one cable is pulled the pulleys will rotate in one direction and when the other cable is pulled the pulleys will rotate in the opposite direction. It will be noted that auxiliary pulleys 9 and 10 guide the cable 8, while auxiliary pulleys 11 and 12 guide the cable 7. If desired, these cables may be connected together, as illustrated at the left in Fig. 1, though this is not essential. When the cable 7 is pulled the curtain 1 is rolled and cable 8 is wound on pulley 6. When cable 8 is pulled the reverse action will take place, namely, the pulleys and roller 2 will rotate in

the reverse direction and allow the curtain 1 to move downwardly.

As shown particularly in Fig. 1, pulley 5 is provided with a hub 13 formed integral therewith and on this hub is arranged a ratchet wheel 14 held against rotation in one direction by a pawl 15 secured to a wall or other suitable support. The ratchet wheel 14 is formed of two parts, namely, part 16 and part 17, said parts being hingedly connected together at 18. A tension screw 19 connects the parts together at a point opposite the hinge 18. A suitable spring 20 provides for a cushioning action in respect to the clamping action of the screw 19. Brake band sections or shoes 21 and 22 are secured respectively to the parts 16 and 17 by suitable screws or other means 23. This brake band structure is adapted to press tightly against the sleeve or hub 13 of pulley 5 which is rigidly secured to roller 2 so that when pulley 5 is rotated in one direction power will be transmitted to the roller 2 so that the roller and also the ratchet wheel will be rotated. However, when the cable 8 is actuated for lowering the curtain 1 the roller 2 will slip in the brake shoe structure formed by members 21 and 22 and associated parts. There is enough friction, however, to stop and hold the curtain at any point. It will be seen, therefore, that when the curtain is raised roller 2 and associated parts freely rotate but when the curtain is lowered roller 2 is rotated against the action of the friction of the brake bands 21 and 22. In the course of time if the parts should become somewhat loose a desired tension may be secured by adjusting the screw 19.

In Fig. 3 a structure is shown wherein ratchet wheel 14 is used but instead of having the brake shoes 21 and 22 engaging the hub 13 the parts are so arranged that these brake shoes will engage directly the roller 2. In Fig. 4 the same structure as shown in Fig. 3 is presented except that the ratchet wheel 14' is provided with a flexible section 14" instead of a hinge 18 as shown in Fig. 2. This form of the invention could be arranged as shown in Fig. 4, namely, with the brake shoes 21 and 22 engaging the roller 2, or the brake shoes could be arranged on the hub 13.

I claim:

1. In a screen control, a pulley provided with a hub, a ratchet wheel mounted on said hub, said ratchet wheel being divided at one point, means for moving said ratchet wheel to close said point of division, a pawl for preventing said ratchet wheel from rotating in one direction and a friction shoe structure connected to said ratchet

wheel and engaging said hub whereby said pulley will rotate freely in one direction and in the other direction will rotate against the action of the friction produced by said friction shoe structure.

5. 2. In a screen control device, a ratchet wheel divided into two parts, means hingedly connecting said parts together at one point, a brake shoe carried by each of said parts interiorly thereof, and a tension screw arranged diametrically opposite said hinged structure for causing said brake shoe to function when the device is in use.

10. 3. A screen control including a ratchet wheel divided at one point and connected at a point diametrically opposite, a screw for drawing together said divided point to reduce the diameter

of the ratchet wheel, and a brake shoe structure carried interiorly of the ratchet wheel.

15. 4. A screen control including a roller, a ratchet wheel mounted on said roller, said ratchet wheel being formed in two parts, a hinge for connecting said parts together at one point, means at a second point for swinging said parts toward each other, a pawl for preventing said ratchet wheel from rotating in one direction and a friction shoe connected to said ratchet wheel interiorly thereof and positioned to engage said roller whereby said pole will be rotated freely in one direction with the ratchet wheel and in the other direction will rotate against the action of the friction produced by said friction shoe.

SYDNEY APPEL.
